(57) CLAIM

The ornamental design for a tattoo pen grip as shown and described.

DESCRIPTION

FIG. 1 is a top view of a tattoo pen grip showing my new design;

FIG. 2 is a side view thereof;

FIG. 3 is a bottom view thereof;

FIG. 4 is a perspective view thereof;

FIG. 5 is a perspective view thereof; and,

FIG. 6 is a side view thereof.

The broken lines shown in FIG. 1 and FIGS. 3-5 illustrate portions of the tattoo pen grip that form no part of the claimed design. The additional broken lines shown in FIGS. 5-6 illustrate environment and form no part of the claimed design.
